The ornamental design for a plunger pot, as shown and described.

DESCRIPTION

FIG. 1 is a perspective view of a plunger pot showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The broken lines shown in the Figures represent portions of the plunger pot that form no part of the claimed design.
